UNITED STATES PATENT OFFICE.

SYLVESTER H. HUNT, OF MILWAUKEE, WISCONSIN.

ORE-LOADER.

1,334,454.

Specification of Letters Patent. Patented Mar. 23, 1920.

Application filed January 14, 1918. Serial No. 271,055.

To all whom it may concern:

Be it known that I, SYLVESTER H. HUNT, a citizen of the United States, residing at Milwaukee, in the county of Milwaukee and State of Wisconsin, have invented certain new and useful Improvements in Ore-Loaders, of which the following is a specification.

The present invention relates more particularly to apparatus for mechanically loading ore or other material into cars, and it is more especially designed for operating in mines or other confined places, though not necessarily limited to such use.

One of the primary objects is to provide an apparatus of this type, in which the conveying mechanism can be laterally swung from side to side of its supporting truck, the delivery end of said conveying mechanism extending beyond the truck so that a car can be placed thereunder, and at the same time to so mount the conveying mechanism that its delivery end will maintain a central position, irrespective of the lateral disposition thereof with respect to the supporting truck.

A further and important object is to provide in apparatus of this character driving mechanism that will operatively accommodate itself to the variations in the relations of the conveying mechanism and truck.

A still further and important object is to provide simple means of an effective character for altering the vertical relation of the digging and conveying mechanism with respect to the truck, and consequently with relation to the surface from which the material is taken.

In the accompanying drawings:—

Figure 1 is a plan view of an embodiment of the invention that is at present considered the preferable one;

Fig. 2 is a side elevation of the same;

Fig. 3 is a longitudinal sectional view;

Fig. 4 is a rear elevation;

Fig. 5 is a detail sectional view on an enlarged scale, illustrating more particularly the driving mechanism for the different instrumentalities.

Fig. 6 is a plan view thereof,

Fig. 7 is a cross sectional view,

Fig. 8 is a horizontal sectional view illustrating more particularly the elevating means,

Fig. 9 is a detail plan view of the delivery end of the conveyor,

Fig. 10 is a side elevation of the same, with a portion shown in section,

Fig. 11 is a detail cross sectional view,

Fig. 12 is a side elevation illustrating an extended overhanging conveyer so that a plurality of cars can be more readily accommodated in the loading operations.

Fig. 13 is a plan view diagrammatic in its character, indicating the action of the conveyer as disclosed in Fig. 12.

Similar reference numerals designate corresponding parts in all the figures of the drawings.

In the embodiment illustrated, a supporting truck member is employed, comprising a body, which includes a platform 13, having an elevated portion 14. This body is supported at one end by driving wheels 15 that may be adapted to operate on the usual track or as ordinary tractor elements, and at the other end by supporting wheels 16. The wheels 16 are carried by a rotating axle 17 journaled in boxes 18 that are vertically slidable in guideways 19 shown more particularly in Fig. 5. The driving wheels 15 are carried by a rotating axle 20.

Mounted upon the truck member is a carriage, designated generally by the reference numeral 21. This carriage includes side frames 22 having horizontal portions 23 that project beyond one end of the truck member, and inclined portions 24 that extend beyond the opposite end of the truck member. The latter end carries a rotatable drum 25 in which are pivoted a plurality of shovel elements 26. These shovel elements are projected by a stationary cam 27 fixed within the drum, and they are also moved inwardly by a roller 28 during the rotation of the drum. The said shovel elements, as will be evident by reference to Fig. 3, are adapted to take up material when projected and carry it over the drum where it will be deposited on an endless conveyer belt 29 mounted on suitable rollers 30 journaled in the side bars 22 of the carriage frame. The rollers, as indicated in Fig. 11 comprise sections arranged in angular relation, so as to give the upper flight of the conveyer a trough-shape. The said conveyer, as indicated in Fig. 3, passes around idler drums 31 and around a terminal drum 32 located in rear of the digger drum 25. At the other end the elevator passes around a drum 33 journaled in boxes 34 that are slidable in 110

guidewalls formed in the ends of the carriage frame 22. Suitable adjusting screws 35 bear against the boxes 34, for the purpose of tightening the conveyer, as will be readily understood. In order that the material will not pass over the edges of the conveyer belt, guide strips 36 are preferably secured upon the upper edges of the side frames 22, and overlap the margins of the conveyer belt 29, as shown in Fig. 11. With this construction, it will be evident that material deposited on the conveyer by the shovel elements 26, will be moved longitudinally over the carriage by means of the said conveyer, and will be delivered from the overhanging rear end of the carriage.

The above described carriage includes a base portion 37, in the form of a casing that has a bearing at 38 and another at 39 on the truck member. The latter bearing constitutes part of a guide way formed of bars 40, secured as shown at 41 transversely on the truck platform. One of these bars has a rack 42 with which meshes a pinion 43 carried by the lower end of a vertical shaft 44 journaled in the carriage base. It will be evident that by operating the pinion 43, the carriage will thus be caused to have a movement transversely or laterally of the truck member. For the purpose of securing this movement, the following mechanism is preferably employed. The upper end of the shaft 44 has secured thereto a pinion 45 that is in mesh with oppositely disposed bevel gears 46 loosely journaled on a horizontal transversely disposed shaft 47. Either of these gears 46 can be clutched to the shaft by suitable clutch elements 48 suitably feathered on said shaft and operated by cam elements 49 located alongside the same and connected by links 50. The link 50 has a connection with a crank 51 carried by a rock shaft 52, and this rock shaft has a gear connection 53 with an actuating shaft 54 projecting beyond the casing or carriage base 37, and provided with a handle lever 55. The lever, as shown especially in Figs. 1 and 4 is disposed adjacent to a platform 56 mounted on one side of the carriage, and on which the operator of the machine stands. With this arrangement, it will be clear that either gear wheel 46 can be driven, and consequently the pinion can be rotated in either of opposite directions, so that the carriage can be moved back or forth. These gears can also both be unclutched from the shaft 47, in which case the pinion is stationary. The shaft 47 is provided at one end with a sprocket wheel 57 around which passes a sprocket chain 58 that also passes around a sprocket wheel 59 on a shaft 60 that is parallel to the shaft 47. The shaft 60 carries a worm wheel 61 which is in mesh with a worm 62 fixed to a counter-shaft 63 journaled

above the worm wheel 61 at right angles to the shafts 47 and 60. The shaft 63 has a coupling 64 adapted to be engaged with the shaft of a motor, indicated at 65, which motor is located within the casing 37 or base of the carriage. While an electric motor is preferably employed, it will be understood that any suitable driving power may be utilized.

The motor shaft 63 carries a second worm 66 which is in mesh with a gear wheel 67 loosely journaled on a shaft 68. This gear wheel 67 can be clutched to the shaft 68 by a member 69 feathered on said shaft. The member 69 is operated by a crank wheel 70 carried by a rock shaft 71 having a crank arm 72, and this crank arm 72 has a link connection 73, as shown in Fig. 7, with a crank on a second rock shaft 74 that projects from one side of the carriage base or casing, and has a pedal 75 for operating it. The shaft 68 is provided at its ends with sprocket wheels 76, around which pass sprocket chains, indicated at 77 in Fig. 3, these sprocket chains operating one of the drums 31, and consequently the conveyer. The terminal drum 32 has sprocket wheels 78, around which pass sprocket chains 79 operating on sprocket wheels 80, fixed to the digging drum 25. With this arrangement, therefore, by clutching the gear 67 to the shaft 68, it will be evident that the digging and conveying mechanism is operated from the motor.

As above explained, the rack and pinion 100 effects a transverse movement of the carriage on the truck member, and mechanism is provided for causing the said carriage to have a swinging movement on an axis at the rear or delivery end of said carriage, 105 and consequently beyond the truck member. This is indicated in dotted lines in Fig. 1, and is accomplished as follows: A link bar 81 is provided having a pivotal connection 82 at its front end with the truck, and 110 having a pivotal connection 83 at its rear end with the bottom of the carriage base. This link is so proportioned that it will swing, as indicated in Fig. 1, to one side or the other accordingly as the digging end 115 of the carriage is swung laterally, and consequently the pivot axis, instead of being directly upon or intersecting one end of the truck, is placed beyond said truck, and at the delivery end of the carriage. It will be 120 evident, therefore, that the delivery end of the carriage maintains a central position with respect to the track, upon which the truck is located, and consequently with respect to the cars placed beneath the same. 125 This central position is maintained entirely irrespective of the distance the receiving or digging end is offset from the truck. There is, however, a tendency of the entire carriage to move bodily in a transverse di- 130

rection from a central position directly over the truck, and to overcome this tendency, the carriage is provided directly adjacent to the ends of the bearing 39 with dependent lugs 84 that abut against the adjacent guide bar. Consequently one or the other of these lugs or projections will bear against the end of the guide bar upon the initial movement of the carriage from the central position, thereby insuring the desired swinging or pivotal movement until an angular relation is reached that will secure a continued pivotal movement without this supplemental aid.

15 Means are also provided for propelling the entire apparatus by the motor, and inasmuch as the pivot axis of the carriage is entirely outside the truck, it will be evident that the transmission gearing between the motor and the driving wheels 15 cannot readily include an element in said pivot axis.

The following mechanism is therefore preferably employed. The shaft 60 is provided with a pair of sprocket wheels 85, around which pass endless sprocket chains 86 that also pass around sprocket wheels 87 fixed to the ends of a transverse shaft 88, and on this shaft are loosely mounted oppositely disposed bevel gears 89 that can be clutched to or unclutched from the shaft by members 90. One of these members is actuated by a swinging arm 91 connected by a link 92 with one arm 93 of a bell crank lever 94. The arm 93 of the bell crank is engaged 35 with the clutch member 90, and said bell crank has a link connection 95 with a crank 96 on a sleeve 97 that surrounds the rock shaft 54. The outer end of this sleeve has secured thereto a pedal 97a. Thus, it will be clear that by operating the pedal 97a, either 40 bevel gear 89 can be clutched to the shaft 88, or both can be loose on said shaft. The bevel gears 89 are in mesh with a gear 98 fixed to the upper end of a vertical shaft 99 45 journaled in the base of the carriage and the lower end of this shaft is provided with a bevel gear 100. There is also rotatably mounted on the lower end of the shaft 99, above the bevel gear 100, a bracket 101 having a horizontal bearing in which is journaled one section 102 of a horizontal shaft, the other section 103 of which is journaled on the under side of the truck member. These two sections are connected by a universal joint coupling 104, one member of 50 which has a socket 105 in which the shaft section 102 has a slidably feathered connection. The section 102 furthermore carries a bevel gear 106 in mesh with the gear 100. 55 The shaft section 103 has a bevel gear 107 fixed thereto, and this gear, as shown more particularly in Fig. 8, is in mesh with a gear 108 loose on the driving axle 20. The gear 108 can be clutched to or unclutched from 60 the axle 20 by the member 109. Therefore,

it will be evident that when the vertical shaft 99 is driven in one direction or the other, the driving wheels will be rotated in one direction or the other, and the entire machine propelled back or forth as desired. 70

In addition, means operated by the motor are provided for effecting the vertical adjustment of the digging end of the apparatus, as is often necessary or desirable, where there is unevenness in the surface 75 from which the material is being removed. As already explained, the boxes 18 of the supporting wheels 16 are vertically movable in guideways 19, as illustrated in Fig. 5, and interposed between said boxes and bearing 80 portions 110 on the truck body, are wedges 111. These wedges are carried by a transverse yoke 112 slidable in the truck frame, and having a central guide portion 113 that is internally threaded to receive an operating 85 screw 114. The said screw 114 is formed upon one end of a shaft, the other end slidably carries a friction clutch member 115 that is movable into and out of co-operation with a mating clutch member 116. The 90 member 116 is fixed to a shaft 117 that carries a bevel gear 118 in mesh with the gear 108. Consequently when said gear is driven, as already described, and the clutch members 115 and 116 are together, the wedges 111 will 95 be moved in one direction or the other, and consequently the truck and the superposed carriage will be elevated or depressed.

It will be evident that the overhanging delivery end of the carriage can be extended 100 considerably, while the pivotal axis of said carriage can be maintained directly at said end. This may be of considerable importance, for it is found that with this apparatus the loading of cars is very greatly 105 facilitated. The maintenance of a supply of cars consequently becomes an important item, and as indicated in Figs. 12 and 13, the extension can be sufficient to permit either loaded or empty cars to be run under the 110 delivery end of the carriage, so that a plurality are successively available, and it is unnecessary to load and remove one at a time. That is to say, with this arrangement illustrated in Fig. 12, two cars as "A" and 115 "B" may be simultaneously run to the delivery end of the apparatus. When one, as "A" is filled, it can be withdrawn until the car "B" is in position to be filled, and when the two have been loaded they may both be 120 removed and replaced by two additional empty cars, thus effecting a material saving in time.

From the foregoing, it is thought that the 125 construction, operation and many advantages of the herein described invention will be apparent to those skilled in the art, without further description, and it will be understood that various changes in the size, shape, proportion and minor details of construc-

tion, may be resorted to without departing from the spirit or sacrificing any of the advantages of the invention.

Having thus fully described my invention, what I claim as new, and desire to secure by Letters Patent, is:—

1. In apparatus of the character set forth, the combination with a truck member, of a carriage laterally movable thereon, means for laterally moving the carriage, means for connecting the carriage and truck member to cause the carriage to have a pivotal movement with the axis of such pivotal movement at one side of said connection, means for moving material along and delivering it from said carriage, a motor, and mechanism for transmitting motion from the motor to the carriage moving means, to the material moving means, and to the truck member for propelling said truck member.
2. In apparatus of the character set forth, the combination with a truck member, of a carriage laterally movable thereon, means for laterally moving the carriage, means for connecting the carriage and truck member to cause the carriage to have a pivotal movement with the axis of such pivotal movement substantially at one side of said carriage and at one side of said connection, means for moving the material along and delivering it from said end of the carriage, a motor, and mechanism for transmitting motion from the motor to the carriage moving means, to the material moving means, irrespective of the position of the carriage on the truck member, and to the truck member for propelling said truck member.
3. In apparatus of the character set forth, the combination with a truck member, of a carriage laterally movable thereon and projecting beyond one end of the same, means for laterally moving the carriage on the truck member, and a connection between the truck member and carriage that causes the carriage to have a pivotal movement with the axis intersecting the projecting end of said carriage, means for moving material along the carriage and delivering it from said projecting end, a motor, and mechanism for transmitting motion from the motor to the carriage moving means, to the material moving means, irrespective of the position of the carriage on the truck member, and to the truck member for propelling said truck member.
4. In apparatus of the character set forth, the combination with a truck member, of a carriage laterally movable thereon, means for laterally moving the carriage on the truck member, and a link connection between the truck member and carriage that causes the latter to have a pivotal swinging movement.
5. In apparatus of the character set forth, the combination with a truck member, of a

carriage laterally movable thereon, operating means mounted on the truck member and carriage for causing a transverse movement of the latter on the former, and a link pivoted to the truck member, and to the carriage for effecting a swinging movement of the carriage when transversely moved by the operating means.

6. In apparatus of the character set forth, the combination with a truck member, of a carriage laterally movable thereon, means for laterally moving the carriage, and means for causing the carriage to swing on a pivot axis that shifts with respect to the truck member.

7. In apparatus of the character set forth, the combination with a truck member, of a carriage laterally movable thereon, a rack and pinion geared between the truck member and carriage for effecting the lateral movement of said carriage, and a link pivoted to the truck member and to the carriage for controlling the movement of the carriage.

8. In apparatus of the character set forth, the combination with a truck member, of a carriage laterally movable thereon, a rack and pinion gear between the truck member and carriage for effecting the lateral movement of the carriage, said carriage projecting beyond one end of the truck member, a link pivoted to the truck member and to the carriage for causing said carriage to have a swinging movement when operated transversely with the axis of such swinging movement in the projecting end of the carriage, and means for conveying material on the carriage and delivering it from the said projecting end.

9. In apparatus of the character set forth, the combination with a truck member, of a carriage having a pivotal mounting thereon, means for moving the carriage, gearing on the truck member, a motor on the carriage, and a transmission member connecting the motor and gearing and located at one side of the axis of movement of the carriage.

10. In apparatus of the character set forth, the combination with a truck member, of a carriage having a pivotal mounting thereon, means for moving the carriage, gearing on the truck member, a motor on the carriage, and an upright transmission shaft constituting a connection between the motor and gearing and located at one side of the axis of movement of the carriage.

11. In apparatus of the character set forth, the combination with a truck member, of a carriage having a pivotal mounting thereon, means for moving the carriage, driving wheels on the truck member, a motor on the carriage, and a transmission gearing between the motor and wheels, including angularly disposed shafts, one on the carriage, the other on the truck member, and a gear con-

nection between the shafts, including a universal joint, and an extension coupling.

12. In apparatus of the character set forth, the combination with a truck member, of a carriage having a pivotal mounting thereon, means for moving the carriage, driving wheels on the truck member, a motor on the carriage, and transmission gearing between the motor and wheels, including an upright shaft on the carriage, a second shaft on the truck member, a universal joint connected to the latter shaft, gearing connected to the first mentioned shaft and an extensible coupling between the gearing and the universal joint.

13. In apparatus of the character set forth, the combination with a truck member, of a carriage having a pivotal mounting thereon, means for moving the carriage, driving wheels on the truck member, a motor on the carriage, and transmission gearing between the motor and wheels, including an upright shaft on the carriage, an angularly disposed shaft on the truck member, comprising sections, and a universal joint and sliding coupling connection between the sections, a bracket connecting adjacent sections of the shaft and rotatable with respect thereto, and gearing connecting adjacent ends of the shaft.

14. In apparatus of the character set forth, the combination with a truck member, and wheels supporting the same of a carriage capable of lateral movement on the truck member, a motor, means driven by the motor for effecting the lateral movements of the carriage, and means on the truck member driven by the motor for elevating the truck member and carriage on the wheels.

15. In apparatus of the character set forth, the combination with a truck member, of a carriage laterally movable thereon and capable of vertical movement, means for elevating the carriage including a wedge, a motor, and means driven by the motor for moving the wedge.

16. In apparatus of the character set forth, the combination with a truck member having driving wheels, of a carriage movably mounted on the truck member, a motor on the carriage, means for elevating the carriage and the truck member on the wheels, and means for driving the wheels from the motor and also for operating the elevating means.

17. In apparatus of the character set forth, the combination with a truck member, of a laterally movable carriage thereon capable of vertical movement, a motor on the carriage, means driven by the motor for effecting the lateral movement of the carriage, means for elevating the carriage, including a wedge, and means driven by the motor for operating the driving wheels and also actuating the wedge.

18. In apparatus of the character set forth, the combination with a truck member, of a set of supporting wheels and a set of driving wheels for the truck member, means for elevating the truck member on the supporting wheels, a carriage movably mounted on the truck member and elevated therewith, a motor on the carriage, and means driven by the motor for actuating the driving wheels and also for actuating the elevating means.

19. In apparatus of the character set forth, the combination with a truck member, of driving wheels and supporting wheels therefor, said truck member being vertically movable on the supporting wheels, a wedge interposed between the supporting wheels and truck member for elevating the latter upon the former, a carriage movably mounted on the truck member, a motor on the carriage, and means operated by the motor for operating the driving wheels and for actuating the wedge.

20. In apparatus of the character set forth, the combination with a truck member, including a body, of driving wheels journaled on the body, supporting wheels for the body, said body being vertically movable on the supporting wheels, a wedge member interposed between the supporting wheels and body for elevating the latter, a swinging carriage on the truck member, a rack and pinion connection between the truck member and carriage for causing a transverse movement of the latter, a link connection between the truck member and carriage for effecting a pivotal movement of the carriage when the rack and pinion connection is actuated, a motor for effecting the operation of the rack and pinion connection, means operated by the motor for actuating the driving wheels and for causing the movement of the wedge, a conveyer mounted on the carriage and delivering from one end of the same, and means operated by the motor for actuating the conveyer.

21. In apparatus of the character set forth, the combination with a truck member, of a carriage mounted thereon and projecting beyond both ends of the same, means for effecting a transverse movement of the carriage on the truck member, connections between the truck member and carriage for causing the latter to have a pivotal movement on an axis that is beyond one end of the truck member, means for conveying material on the carriage and delivering it from said end, a motor, and mechanism for transmitting motion from the motor to the carriage moving means, to the material conveying means, irrespective of the position of the carriage on the truck member, and to the truck member for propelling said truck member.

22. In apparatus of the character set forth,

forth, the combination with a truck member, of a carriage mounted thereon and projecting beyond both ends of the same, means on the carriage for conveying material thereon 5 and delivering it from one of the projecting ends, means on the other projecting end for placing material on the conveying means, the delivery end of said carriage projecting beyond the truck member a sufficient distance to permit at least one of a plurality of 10 cars to be placed thereunder at one end of the truck member with the material conveying means in a position to deliver to a second car adjacent to the car beneath said projecting end, means for effecting a transverse movement of the carriage on the truck member, and means for causing the truck member to have a swinging movement on an upright axis that maintains the projecting delivery end portion of the carriage at a sub-

stantially fixed point above such second car placed beneath the said delivery end.

23. In apparatus of the character set forth, the combination with a truck, of a shiftable carriage mounted thereon and extending beyond the truck at its delivery end, conveying means on the carriage, means associated with the truck and carriage for laterally adjusting said carriage relative to the truck about an axis at its delivery end and 25 maintaining a constant point of discharge beyond the rear end of the aforesaid truck, a motor member, and means operated by the motor member for propelling the truck and for operating the conveyer means irrespective of the lateral adjustment of the carriage. 30

In testimony whereof, I affix my signature.

SYLVESTER H. HUNT.
